INTERLEAVING DEVICE.

Application filed August 15, 1927. Serial No 213,163.

The invention relates to interleaving devices and particularly to means for preventing offset or blurring between freshly inked sheets, such as are delivered by duplicating machines and the like. The development in the art of multiplying copies has resulted in sheets being delivered so rapidly that one sheet is apt to contact with another before the ink is dry, and sundry suggestions have been made contemplating the interleaving of the sheets with blotters or the like to prevent smudging. None of the means heretofore suggested has been found sufficiently efficient and practicable, the shortcomings resulting from one or more of a variety of defects such as the character of the separator introduced between the sheets, the means for detaching each separator from the stack, the dependence on gravity alone for delivering the separator, inefficient provision for timing, or the complication and cost of the mechanism. The general objects of the present invention are to provide means for preventing offset or smudging between such sheets, which avoid the shortcomings of prior suggestions and may be used and operated more rapidly and efficiently and without undue cost.

With these and other objects in view, the invention comprises a suitable separator, means for holding a stack or collection of such separators and detaching a single separator from the stack, means for positively or forcibly delivering the separator, and means incidental to the foregoing, all properly actuated and timed by suitable connection with the machine delivering the sheets. In the accompanying drawing one preferred form of the invention is illustrated. Fig. 1 is a side elevation of the mechanism, with the parts in the position assumed just prior to detaching one separator from the stack, shown assembled with a part of any duplicating or other machine delivering sheets; Fig. 2 is a view of a separator on top of a stack of interleaved separators and sheets; Fig. 3 is a section on line 3—3 of Fig. 9; Fig. 4 is a partial side elevation showing the parts in the position assumed at the beginning of the detaching of one separator from the stack; Fig. 5 is a similar partial elevation from the side opposite that shown in Fig. 4, with the parts in the position assumed just before the positive delivery of the separator;

Fig. 6 is a detail of the member holding and assisting in detaching the separator from the stack; Fig. 7 is a section on line 7—7 of Fig. 1; Fig. 8 is a rear elevation of the mechanism shown in Fig. 1; Fig. 9 is a section on line 9—9 of Fig. 1; and Figs. 10 and 11 are enlarged details of the grippers.

The separator 1 illustrated in Fig. 2 consists of a piece of material of a size suitable for interleaving between the sheets but preferably differing from the sheet in shape or size so as to leave a portion of the sheet uncovered, as by the omission of a corner of the separator, as at 3, or by making the separator narrower than the sheet or extending beyond it, as at 2, to facilitate the easy removal of the separators from the sheets after the ink on the sheets has dried. The chief function of the separator is to keep the sheets apart to permit drying of the ink, and it may accordingly be made of any suitable material, preferably strawboard paper or other material of sufficient stiffness to make most effective the operation of the positive delivery means hereinafter described, and, for the same purpose, is provided with a hole 4 near its center when the particular delivery means illustrated are used.

The means for holding a stack of separators and detaching a single separator therefrom, comprise a receptacle 5 adapted to hold the stack and mechanism to remove a single separator. The receptacle illustrated comprises a bottom upon which the separators stand, having a catch or stop 6, together with spring-pressed means, as 32, keeping the catch in contact with the stack after separators are removed therefrom; a frame 8; and a spring-pressed member 9 (shown in detail in Fig. 6) extending over the top of the stack so that when a separator is elevated thereagainst, its top is moved out from the stack to admit air between it and the stack and it is then forced downward and outside the catch 6, to insure efficient detachment from the stack and operation of the delivery means. The mechanism for moving the separator against the spring-pressed member 9 comprises gripping members 10 (as in the form illustrated in detail in Figs. 10 and 11) made of rubber or comprising metal teeth and mounted and actuated so as to be brought into contact with the face of the outside separator

of the stack and elevate that separator, in proper timing with the operations as herein-after described.

These holding and detaching means are mounted at an appropriate distance from the sheet delivering machine, as by brackets 11, and separated therefrom by a receiving table 12, also conveniently mounted by attachment to the sheet delivering machine and the separator receptacle, and preferably provided with a drawer for the convenient removal of the interleaved stack. The gripping members 10 are shown mounted on arms 13 on the yoke 14 supported by arms 15 pivotally mounted on a bell crank mechanism 16 on the shaft 17 moved by a connection 18 with a crank 19 on the gear shaft of the sheet feeding mechanism so that a separator is elevated and detached from the stack at the proper time with respect to the feeding of the sheet. The torsion springs 37 permit the arms 15 to yield relatively to the crank arms 16.

The means for delivering the separator are shown as consisting of a plunger 20 carried by a crank 21 mounted on a shaft 22, the plunger being so positioned as to pass through the hole 4 in the separators when stacked in the receptacle 5. The shaft 22 is mounted on the frame and provided with a crank 23 connected by a spring-pressed arm 24 to a lever 25 mounted on the support of the sheet delivering machine and carrying a roll bearing against a cam or roller 26 with a drop therein mounted on the gear shaft, so that as a sheet is fed at the proper time the drop in the roller 26 permits the spring to move the arm 24, turning the shaft 22 and moving the plunger 20 against the separator (which at that stage of the operation has descended so that the end of the plunger contacts with a portion above the hole) exerting force thereon to insure its rapid delivery on top of the sheet. On the shaft 22 there are preferably also mounted two side guides 27 moving as the plunger moves and further insuring accuracy in delivering the separator.

To prevent interference by the gripping member mechanism with the delivery of the separators, provision is made for moving and keeping that mechanism out of reach of the separator during its downward movement, illustrated as comprising providing one side of the arms of the yoke 14 with a pin 28 engaged by a cam 29 fixed to the frame to force the yoke 14 out from the stack (when the operation has reached a stage where the separator has been detached from the stack and moved downward and before the plunger contacts therewith) and providing the other side of the arms of the yoke 14 with a pin 30 engaged by a notch in a gravity arm 31 mounted on the frame and adapted to hold the yoke away from the separator until the downward movement of the arm 15 causes the pin to leave the notch, prior to the begin-

ning of a fresh cycle of the operation. The arm 31 is pivotally mounted on the frame 8, and its normal position is determined by the stop 36 fixed to the frame. On the upward movement of the arms 15 the pin 30 ⁷⁰ engages the arm 31 and lifts it until the pin 30 enters the notch in the end of the arm, at which time the arms 15 have completed their upward movement. The pin 30 ⁷⁵ remains in the notch in the end of the arm 31 as the arms 15 move downwardly and consequently the arms 15 are forced outwardly clear of the stack of separators until the arm 31 encounters the stop 36. Thereupon further continued downward movement ⁸⁰ of the arms 15 frees the pin 30 from the notch in the arm 31, permitting the springs 37 to move the arms 15 inwardly to bring the gripping members 10 into engagement with the outermost separator. ⁸⁵

To insure accuracy of operation it is preferable to provide for the intermittent compression of the bottom of the stack of separators, as illustrated particularly in Fig. 3, wherein the tension lever 32 fulcrumed on the frame with one arm bearing against the stack and the other arm provided with a spring 33, is also provided with an arm 34 engaged by a crank 35 on the shaft 17 carrying the bell crank mechanism 16, so that the pressure on the separators against the catch 6 is removed at that stage of the operation when one of the separators is to be moved upward by the gripping members and reapplied in time to prevent its reentry behind the catch. The inclined position of the table 12 illustrated is preferable, because it permits of handling long and short sheets without adjustment. But it will be understood that the invention may be used in forms ⁹⁵ not embodying the details and refinements of the preferred forms herein illustrated. ¹⁰

The operation of the mechanism will be apparent from the drawings and description. As the sheet (indicated by dotted lines in Fig. 3) is fed from the sheet producing machine, a separator is detached from the stack by the movement of the crank 19 through its connections with the gripping members 10, forcing a separator up against the resilient member 9 which causes it to move outwardly and then imparts positive downward motion to it, so that it descends until one end rests on the end of the sheet on the receiving table, whereupon force in addition to gravity is applied to it by the plunger 20 to further its fall and delivery on top of the sheet. It is to be observed that the separator is simple, inexpensive and particularly adapted to the practice of this invention and that provision is made for positively detaching it from the stack and positively delivering it to the sheet in such fashion that it rolls from its bottom without sliding motion likely to produce smirching, and thus offset or burring between ¹¹ ¹² ¹³ ¹⁴ ¹⁵ ¹⁶ ¹⁷ ¹⁸ ¹⁹ ²⁰ ²¹ ²² ²³ ²⁴ ²⁵ ²⁶ ²⁷ ²⁸ ²⁹ ³⁰ ³¹ ³² ³³ ³⁴ ³⁵ ³⁶ ³⁷ ³⁸ ³⁹ ⁴⁰ ⁴¹ ⁴² ⁴³ ⁴⁴ ⁴⁵ ⁴⁶ ⁴⁷ ⁴⁸ ⁴⁹ ⁵⁰ ⁵¹ ⁵² ⁵³ ⁵⁴ ⁵⁵ ⁵⁶ ⁵⁷ ⁵⁸ ⁵⁹ ⁶⁰ ⁶¹ ⁶² ⁶³ ⁶⁴ ⁶⁵ ⁶⁶ ⁶⁷ ⁶⁸ ⁶⁹ ⁷⁰ ⁷¹ ⁷² ⁷³ ⁷⁴ ⁷⁵ ⁷⁶ ⁷⁷ ⁷⁸ ⁷⁹ ⁸⁰ ⁸¹ ⁸² ⁸³ ⁸⁴ ⁸⁵ ⁸⁶ ⁸⁷ ⁸⁸ ⁸⁹ ⁹⁰ ⁹¹ ⁹² ⁹³ ⁹⁴ ⁹⁵ ⁹⁶ ⁹⁷ ⁹⁸ ⁹⁹ ¹⁰⁰ ¹⁰¹ ¹⁰² ¹⁰³ ¹⁰⁴ ¹⁰⁵ ¹⁰⁶ ¹⁰⁷ ¹⁰⁸ ¹⁰⁹ ¹¹⁰ ¹¹¹ ¹¹² ¹¹³ ¹¹⁴ ¹¹⁵ ¹¹⁶ ¹¹⁷ ¹¹⁸ ¹¹⁹ ¹²⁰ ¹²¹ ¹²² ¹²³ ¹²⁴ ¹²⁵ ¹²⁶ ¹²⁷ ¹²⁸ ¹²⁹ ¹³⁰ ¹³¹ ¹³² ¹³³ ¹³⁴ ¹³⁵ ¹³⁶ ¹³⁷ ¹³⁸ ¹³⁹ ¹⁴⁰ ¹⁴¹ ¹⁴² ¹⁴³ ¹⁴⁴ ¹⁴⁵ ¹⁴⁶ ¹⁴⁷ ¹⁴⁸ ¹⁴⁹ ¹⁵⁰ ¹⁵¹ ¹⁵² ¹⁵³ ¹⁵⁴ ¹⁵⁵ ¹⁵⁶ ¹⁵⁷ ¹⁵⁸ ¹⁵⁹ ¹⁶⁰ ¹⁶¹ ¹⁶² ¹⁶³ ¹⁶⁴ ¹⁶⁵ ¹⁶⁶ ¹⁶⁷ ¹⁶⁸ ¹⁶⁹ ¹⁷⁰ ¹⁷¹ ¹⁷² ¹⁷³ ¹⁷⁴ ¹⁷⁵ ¹⁷⁶ ¹⁷⁷ ¹⁷⁸ ¹⁷⁹ ¹⁸⁰ ¹⁸¹ ¹⁸² ¹⁸³ ¹⁸⁴ ¹⁸⁵ ¹⁸⁶ ¹⁸⁷ ¹⁸⁸ ¹⁸⁹ ¹⁹⁰ ¹⁹¹ ¹⁹² ¹⁹³ ¹⁹⁴ ¹⁹⁵ ¹⁹⁶ ¹⁹⁷ ¹⁹⁸ ¹⁹⁹ ²⁰⁰ ²⁰¹ ²⁰² ²⁰³ ²⁰⁴ ²⁰⁵ ²⁰⁶ ²⁰⁷ ²⁰⁸ ²⁰⁹ ²¹⁰ ²¹¹ ²¹² ²¹³ ²¹⁴ ²¹⁵ ²¹⁶ ²¹⁷ ²¹⁸ ²¹⁹ ²²⁰ ²²¹ ²²² ²²³ ²²⁴ ²²⁵ ²²⁶ ²²⁷ ²²⁸ ²²⁹ ²³⁰ ²³¹ ²³² ²³³ ²³⁴ ²³⁵ ²³⁶ ²³⁷ ²³⁸ ²³⁹ ²⁴⁰ ²⁴¹ ²⁴² ²⁴³ ²⁴⁴ ²⁴⁵ ²⁴⁶ ²⁴⁷ ²⁴⁸ ²⁴⁹ ²⁵⁰ ²⁵¹ ²⁵² ²⁵³ ²⁵⁴ ²⁵⁵ ²⁵⁶ ²⁵⁷ ²⁵⁸ ²⁵⁹ ²⁶⁰ ²⁶¹ ²⁶² ²⁶³ ²⁶⁴ ²⁶⁵ ²⁶⁶ ²⁶⁷ ²⁶⁸ ²⁶⁹ ²⁷⁰ ²⁷¹ ²⁷² ²⁷³ ²⁷⁴ ²⁷⁵ ²⁷⁶ ²⁷⁷ ²⁷⁸ ²⁷⁹ ²⁸⁰ ²⁸¹ ²⁸² ²⁸³ ²⁸⁴ ²⁸⁵ ²⁸⁶ ²⁸⁷ ²⁸⁸ ²⁸⁹ ²⁹⁰ ²⁹¹ ²⁹² ²⁹³ ²⁹⁴ ²⁹⁵ ²⁹⁶ ²⁹⁷ ²⁹⁸ ²⁹⁹ ³⁰⁰ ³⁰¹ ³⁰² ³⁰³ ³⁰⁴ ³⁰⁵ ³⁰⁶ ³⁰⁷ ³⁰⁸ ³⁰⁹ ³¹⁰ ³¹¹ ³¹² ³¹³ ³¹⁴ ³¹⁵ ³¹⁶ ³¹⁷ ³¹⁸ ³¹⁹ ³²⁰ ³²¹ ³²² ³²³ ³²⁴ ³²⁵ ³²⁶ ³²⁷ ³²⁸ ³²⁹ ³³⁰ ³³¹ ³³² ³³³ ³³⁴ ³³⁵ ³³⁶ ³³⁷ ³³⁸ ³³⁹ ³⁴⁰ ³⁴¹ ³⁴² ³⁴³ ³⁴⁴ ³⁴⁵ ³⁴⁶ ³⁴⁷ ³⁴⁸ ³⁴⁹ ³⁵⁰ ³⁵¹ ³⁵² ³⁵³ ³⁵⁴ ³⁵⁵ ³⁵⁶ ³⁵⁷ ³⁵⁸ ³⁵⁹ ³⁶⁰ ³⁶¹ ³⁶² ³⁶³ ³⁶⁴ ³⁶⁵ ³⁶⁶ ³⁶⁷ ³⁶⁸ ³⁶⁹ ³⁷⁰ ³⁷¹ ³⁷² ³⁷³ ³⁷⁴ ³⁷⁵ ³⁷⁶ ³⁷⁷ ³⁷⁸ ³⁷⁹ ³⁸⁰ ³⁸¹ ³⁸² ³⁸³ ³⁸⁴ ³⁸⁵ ³⁸⁶ ³⁸⁷ ³⁸⁸ ³⁸⁹ ³⁹⁰ ³⁹¹ ³⁹² ³⁹³ ³⁹⁴ ³⁹⁵ ³⁹⁶ ³⁹⁷ ³⁹⁸ ³⁹⁹ ⁴⁰⁰ ⁴⁰¹ ⁴⁰² ⁴⁰³ ⁴⁰⁴ ⁴⁰⁵ ⁴⁰⁶ ⁴⁰⁷ ⁴⁰⁸ ⁴⁰⁹ ⁴¹⁰ ⁴¹¹ ⁴¹² ⁴¹³ ⁴¹⁴ ⁴¹⁵ ⁴¹⁶ ⁴¹⁷ ⁴¹⁸ ⁴¹⁹ ⁴²⁰ ⁴²¹ ⁴²² ⁴²³ ⁴²⁴ ⁴²⁵ ⁴²⁶ ⁴²⁷ ⁴²⁸ ⁴²⁹ ⁴³⁰ ⁴³¹ ⁴³² ⁴³³ ⁴³⁴ ⁴³⁵ ⁴³⁶ ⁴³⁷ ⁴³⁸ ⁴³⁹ ⁴⁴⁰ ⁴⁴¹ ⁴⁴² ⁴⁴³ ⁴⁴⁴ ⁴⁴⁵ ⁴⁴⁶ ⁴⁴⁷ ⁴⁴⁸ ⁴⁴⁹ ⁴⁵⁰ ⁴⁵¹ ⁴⁵² ⁴⁵³ ⁴⁵⁴ ⁴⁵⁵ ⁴⁵⁶ ⁴⁵⁷ ⁴⁵⁸ ⁴⁵⁹ ⁴⁶⁰ ⁴⁶¹ ⁴⁶² ⁴⁶³ ⁴⁶⁴ ⁴⁶⁵ ⁴⁶⁶ ⁴⁶⁷ ⁴⁶⁸ ⁴⁶⁹ ⁴⁷⁰ ⁴⁷¹ ⁴⁷² ⁴⁷³ ⁴⁷⁴ ⁴⁷⁵ ⁴⁷⁶ ⁴⁷⁷ ⁴⁷⁸ ⁴⁷⁹ ⁴⁸⁰ ⁴⁸¹ ⁴⁸² ⁴⁸³ ⁴⁸⁴ ⁴⁸⁵ ⁴⁸⁶ ⁴⁸⁷ ⁴⁸⁸ ⁴⁸⁹ ⁴⁹⁰ ⁴⁹¹ ⁴⁹² ⁴⁹³ ⁴⁹⁴ ⁴⁹⁵ ⁴⁹⁶ ⁴⁹⁷ ⁴⁹⁸ ⁴⁹⁹ ⁵⁰⁰ ⁵⁰¹ ⁵⁰² ⁵⁰³ ⁵⁰⁴ ⁵⁰⁵ ⁵⁰⁶ ⁵⁰⁷ ⁵⁰⁸ ⁵⁰⁹ ⁵¹⁰ ⁵¹¹ ⁵¹² ⁵¹³ ⁵¹⁴ ⁵¹⁵ ⁵¹⁶ ⁵¹⁷ ⁵¹⁸ ⁵¹⁹ ⁵²⁰ ⁵²¹ ⁵²² ⁵²³ ⁵²⁴ ⁵²⁵ ⁵²⁶ ⁵²⁷ ⁵²⁸ ⁵²⁹ ⁵³⁰ ⁵³¹ ⁵³² ⁵³³ ⁵³⁴ ⁵³⁵ ⁵³⁶ ⁵³⁷ ⁵³⁸ ⁵³⁹ ⁵⁴⁰ ⁵⁴¹ ⁵⁴² ⁵⁴³ ⁵⁴⁴ ⁵⁴⁵ ⁵⁴⁶ ⁵⁴⁷ ⁵⁴⁸ ⁵⁴⁹ ⁵⁵⁰ ⁵⁵¹ ⁵⁵² ⁵⁵³ ⁵⁵⁴ ⁵⁵⁵ ⁵⁵⁶ ⁵⁵⁷ ⁵⁵⁸ ⁵⁵⁹ ⁵⁶⁰ ⁵⁶¹ ⁵⁶² ⁵⁶³ ⁵⁶⁴ ⁵⁶⁵ ⁵⁶⁶ ⁵⁶⁷ ⁵⁶⁸ ⁵⁶⁹ ⁵⁷⁰ ⁵⁷¹ ⁵⁷² ⁵⁷³ ⁵⁷⁴ ⁵⁷⁵ ⁵⁷⁶ ⁵⁷⁷ ⁵⁷⁸ ⁵⁷⁹ ⁵⁸⁰ ⁵⁸¹ ⁵⁸² ⁵⁸³ ⁵⁸⁴ ⁵⁸⁵ ⁵⁸⁶ ⁵⁸⁷ ⁵⁸⁸ ⁵⁸⁹ ⁵⁹⁰ ⁵⁹¹ ⁵⁹² ⁵⁹³ ⁵⁹⁴ ⁵⁹⁵ ⁵⁹⁶ ⁵⁹⁷ ⁵⁹⁸ ⁵⁹⁹ ⁶⁰⁰ ⁶⁰¹ ⁶⁰² ⁶⁰³ ⁶⁰⁴ ⁶⁰⁵ ⁶⁰⁶ ⁶⁰⁷ ⁶⁰⁸ ⁶⁰⁹ ⁶¹⁰ ⁶¹¹ ⁶¹² ⁶¹³ ⁶¹⁴ ⁶¹⁵ ⁶¹⁶ ⁶¹⁷ ⁶¹⁸ ⁶¹⁹ ⁶²⁰ ⁶²¹ ⁶²² ⁶²³ ⁶²⁴ ⁶²⁵ ⁶²⁶ ⁶²⁷ ⁶²⁸ ⁶²⁹ ⁶³⁰ ⁶³¹ ⁶³² ⁶³³ ⁶³⁴ ⁶³⁵ ⁶³⁶ ⁶³⁷ ⁶³⁸ ⁶³⁹ ⁶⁴⁰ ⁶⁴¹ ⁶⁴² ⁶⁴³ ⁶⁴⁴ ⁶⁴⁵ ⁶⁴⁶ ⁶⁴⁷ ⁶⁴⁸ ⁶⁴⁹ ⁶⁵⁰ ⁶⁵¹ ⁶⁵² ⁶⁵³ ⁶⁵⁴ ⁶⁵⁵ ⁶⁵⁶ ⁶⁵⁷ ⁶⁵⁸ ⁶⁵⁹ ⁶⁶⁰ ⁶⁶¹ ⁶⁶² ⁶⁶³ ⁶⁶⁴ ⁶⁶⁵ ⁶⁶⁶ ⁶⁶⁷ ⁶⁶⁸ ⁶⁶⁹ ⁶⁷⁰ ⁶⁷¹ ⁶⁷² ⁶⁷³ ⁶⁷⁴ ⁶⁷⁵ ⁶⁷⁶ ⁶⁷⁷ ⁶⁷⁸ ⁶⁷⁹ ⁶⁸⁰ ⁶⁸¹ ⁶⁸² ⁶⁸³ ⁶⁸⁴ ⁶⁸⁵ ⁶⁸⁶ ⁶⁸⁷ ⁶⁸⁸ ⁶⁸⁹ ⁶⁹⁰ ⁶⁹¹ ⁶⁹² ⁶⁹³ ⁶⁹⁴ ⁶⁹⁵ ⁶⁹⁶ ⁶⁹⁷ ⁶⁹⁸ ⁶⁹⁹ ⁷⁰⁰ ⁷⁰¹ ⁷⁰² ⁷⁰³ ⁷⁰⁴ ⁷⁰⁵ ⁷⁰⁶ ⁷⁰⁷ ⁷⁰⁸ ⁷⁰⁹ ⁷¹⁰ ⁷¹¹ ⁷¹² ⁷¹³ ⁷¹⁴ ⁷¹⁵ ⁷¹⁶ ⁷¹⁷ ⁷¹⁸ ⁷¹⁹ ⁷²⁰ ⁷²¹ ⁷²² ⁷²³ ⁷²⁴ ⁷²⁵ ⁷²⁶ ⁷²⁷ ⁷²⁸ ⁷²⁹ ⁷³⁰ ⁷³¹ ⁷³² ⁷³³ ⁷³⁴ ⁷³⁵ ⁷³⁶ ⁷³⁷ ⁷³⁸ ⁷³⁹ ⁷⁴⁰ ⁷⁴¹ ⁷⁴² ⁷⁴³ ⁷⁴⁴ ⁷⁴⁵ ⁷⁴⁶ ⁷⁴⁷ ⁷⁴⁸ ⁷⁴⁹ ⁷⁵⁰ ⁷⁵¹ ⁷⁵² ⁷⁵³ ⁷⁵⁴ ⁷⁵⁵ ⁷⁵⁶ ⁷⁵⁷ ⁷⁵⁸ ⁷⁵⁹ ⁷⁶⁰ ⁷⁶¹ ⁷⁶² ⁷⁶³ ⁷⁶⁴ ⁷⁶⁵ ⁷⁶⁶ ⁷⁶⁷ ⁷⁶⁸ ⁷⁶⁹ ⁷⁷⁰ ⁷⁷¹ ⁷⁷² ⁷⁷³ ⁷⁷⁴ ⁷⁷⁵ ⁷⁷⁶ ⁷⁷⁷ ⁷⁷⁸ ⁷⁷⁹ ⁷⁸⁰ ⁷⁸¹ ⁷⁸² ⁷⁸³ ⁷⁸⁴ ⁷⁸⁵ ⁷⁸⁶ ⁷⁸⁷ ⁷⁸⁸ ⁷⁸⁹ ⁷⁹⁰ ⁷⁹¹ ⁷⁹² ⁷⁹³ ⁷⁹⁴ ⁷⁹⁵ ⁷⁹⁶ ⁷⁹⁷ ⁷⁹⁸ ⁷⁹⁹ ⁸⁰⁰ ⁸⁰¹ ⁸⁰² ⁸⁰³ ⁸⁰⁴ ⁸⁰⁵ ⁸⁰⁶ ⁸⁰⁷ ⁸⁰⁸ ⁸⁰⁹ ⁸¹⁰ ⁸¹¹ ⁸¹² ⁸¹³ ⁸¹⁴ ⁸¹⁵ ⁸¹⁶ ⁸¹⁷ ⁸¹⁸ ⁸¹⁹ ⁸²⁰ ⁸²¹ ⁸²² ⁸²³ ⁸²⁴ ⁸²⁵ ⁸²⁶ ⁸²⁷ ⁸²⁸ ⁸²⁹ ⁸³⁰ ⁸³¹ ⁸³² ⁸³³ ⁸³⁴ ⁸³⁵ ⁸³⁶ ⁸³⁷ ⁸³⁸ ⁸³⁹ ⁸⁴⁰ ⁸⁴¹ ⁸⁴² ⁸⁴³ ⁸⁴⁴ ⁸⁴⁵ ⁸⁴⁶ ⁸⁴⁷ ⁸⁴⁸ ⁸⁴⁹ ⁸⁵⁰ ⁸⁵¹ ⁸⁵² ⁸⁵³ ⁸⁵⁴ ⁸⁵⁵ ⁸⁵⁶ ⁸⁵⁷ ⁸⁵⁸ ⁸⁵⁹ ⁸⁶⁰ ⁸⁶¹ ⁸⁶² ⁸⁶³ ⁸⁶⁴ ⁸⁶⁵ ⁸⁶⁶ ⁸⁶⁷ ⁸⁶⁸ ⁸⁶⁹ ⁸⁷⁰ ⁸⁷¹ ⁸⁷² ⁸⁷³ ⁸⁷⁴ ⁸⁷⁵ ⁸⁷⁶ ⁸⁷⁷ ⁸⁷⁸ ⁸⁷⁹ ⁸⁸⁰ ⁸⁸¹ ⁸⁸² ⁸⁸³ ⁸⁸⁴ ⁸⁸⁵ ⁸⁸⁶ ⁸⁸⁷ ⁸⁸⁸ ⁸⁸⁹ ⁸⁹⁰ ⁸⁹¹ ⁸⁹² ⁸⁹³ ⁸⁹⁴ ⁸⁹⁵ ⁸⁹⁶ ⁸⁹⁷ ⁸⁹⁸ ⁸⁹⁹ ⁹⁰⁰ ⁹⁰¹ ⁹⁰² ⁹⁰³ ⁹⁰⁴ ⁹⁰⁵ ⁹⁰⁶ ⁹⁰⁷ ⁹⁰⁸ ⁹⁰⁹ ⁹¹⁰ ⁹¹¹ ⁹¹² ⁹¹³ ⁹¹⁴ ⁹¹⁵ ⁹¹⁶ ⁹¹⁷ ⁹¹⁸ ⁹¹⁹ ⁹²⁰ ⁹²¹ ⁹²² ⁹²³ ⁹²⁴ ⁹²⁵ ⁹²⁶ ⁹²⁷ ⁹²⁸ ⁹²⁹ ⁹³⁰ ⁹³¹ ⁹³² ⁹³³ ⁹³⁴ ⁹³⁵ ⁹³⁶ ⁹³⁷ ⁹³⁸ ⁹³⁹ ⁹⁴⁰ ⁹⁴¹ ⁹⁴² ⁹⁴³ ⁹⁴⁴ ⁹⁴⁵ ⁹⁴⁶ ⁹⁴⁷ ⁹⁴⁸ ⁹⁴⁹ ⁹⁵⁰ ⁹⁵¹ ⁹⁵² ⁹⁵³ ⁹⁵⁴ ⁹⁵⁵ ⁹⁵⁶ ⁹⁵⁷ ⁹⁵⁸ ⁹⁵⁹ ⁹⁶⁰ ⁹⁶¹ ⁹⁶² ⁹⁶³ ⁹⁶⁴ ⁹⁶⁵ ⁹⁶⁶ ⁹⁶⁷ ⁹⁶⁸ ⁹⁶⁹ ⁹⁷⁰ ⁹⁷¹ ⁹⁷² ⁹⁷³ ⁹⁷⁴ ⁹⁷⁵ ⁹⁷⁶ ⁹⁷⁷ ⁹⁷⁸ ⁹⁷⁹ ⁹⁸⁰ ⁹⁸¹ ⁹⁸² ⁹⁸³ ⁹⁸⁴ ⁹⁸⁵ ⁹⁸⁶ ⁹⁸⁷ ⁹⁸⁸ ⁹⁸⁹ ⁹⁹⁰ ⁹⁹¹ ⁹⁹² ⁹⁹³ ⁹⁹⁴ ⁹⁹⁵ ⁹⁹⁶ ⁹⁹⁷ ⁹⁹⁸ ⁹⁹⁹ ¹⁰⁰⁰ ¹⁰⁰¹ ¹⁰⁰² ¹⁰⁰³ ¹⁰⁰⁴ ¹⁰⁰⁵ ¹⁰⁰⁶ ¹⁰⁰⁷ ¹⁰⁰⁸ ¹⁰⁰⁹ ¹⁰¹⁰ ¹⁰¹¹ ¹⁰¹² ¹⁰¹³ ¹⁰¹⁴ ¹⁰¹⁵ ¹⁰¹⁶ ¹⁰¹⁷ ¹⁰¹⁸ ¹⁰¹⁹ ¹⁰²⁰ ¹⁰²¹ ¹⁰²² ¹⁰²³ ¹⁰²⁴ ¹⁰²⁵ ¹⁰²⁶ ¹⁰²⁷ ¹⁰²⁸ ¹⁰²⁹ ¹⁰³⁰ ¹⁰³¹ ¹⁰³² ¹⁰³³ ¹⁰³⁴ ¹⁰³⁵ ¹⁰³⁶ ¹⁰³⁷ ¹⁰³⁸ ¹⁰³⁹ ¹⁰⁴⁰ ¹⁰⁴¹ ¹⁰⁴² ¹⁰⁴³ ¹⁰⁴⁴ ¹⁰⁴⁵ ¹⁰⁴⁶ ¹⁰⁴⁷ ¹⁰⁴⁸ ¹⁰⁴⁹ ¹⁰⁵⁰ ¹⁰⁵¹ ¹⁰⁵² ¹⁰⁵³ ¹⁰⁵⁴ ¹⁰⁵⁵ ¹⁰⁵⁶ ¹⁰⁵⁷ ¹⁰⁵⁸ ¹⁰⁵⁹ ¹⁰⁶⁰ ¹⁰⁶¹ ¹⁰⁶² ¹⁰⁶³ ¹⁰⁶⁴ ¹⁰⁶⁵ ¹⁰⁶⁶ ¹⁰⁶⁷ ¹⁰⁶⁸ ¹⁰⁶⁹ ¹⁰⁷⁰ ¹⁰⁷¹ ¹⁰⁷² ¹⁰⁷³ ¹⁰⁷⁴ ¹⁰⁷⁵ ¹⁰⁷⁶ ¹⁰⁷⁷ ¹⁰⁷⁸ ¹⁰⁷⁹ ¹⁰⁸⁰ ¹⁰⁸¹ ¹⁰⁸² ¹⁰⁸³ ¹⁰⁸⁴ ¹⁰⁸⁵ ¹⁰⁸⁶ ¹⁰⁸⁷ ¹⁰⁸⁸ ¹⁰⁸⁹ ¹⁰⁹⁰ ¹⁰⁹¹ ¹⁰⁹² ¹⁰⁹³ ¹⁰⁹⁴ ¹⁰⁹⁵ ¹⁰⁹⁶ ¹⁰⁹⁷ ¹⁰⁹⁸ ¹⁰⁹⁹

freshly inked sheets however rapidly delivered, may be efficiently prevented.

The following claims are made:—

1. A device for inserting separators between successively delivered sheets, comprising means for holding a collection of separators above a table receiving the sheets, means for releasing a separator from the collection to descend on its end to a sheet on the receiving table, and means for exerting force against the descended separator to assist it to a position parallel to the table.

2. A device for inserting separators between successively delivered sheets, comprising means for holding a collection of separators above a table receiving the sheets, means for detaching a separator from the collection and exerting force thereagainst to further its descent to a position wherein its end rests on a sheet on the table, and means for causing said separator to fall to a position parallel to the table.

3. A device for inserting separators between successively delivered sheets, comprising means for holding a collection of separators, means for releasing a separator from the collection and means for exerting force against the released separator in a direction to assist in delivering it to a delivered sheet.

4. A device for inserting separators between successively delivered sheets, comprising means for holding a collection of separators, means connected with and actuated by the sheet delivering mechanism for detaching a separator from the collection, and means connected with and timed by the sheet delivering mechanism for exerting force against the separator in a direction to assist in delivering it to a delivered sheet.

5. In a device for inserting separators between successively delivered sheets, a platform to support a stack of separators having a retaining stop at the edge thereof, and means to secure contact between said stop and the stack after the removal of a separator therefrom, in combination with means to elevate a separator to permit its bottom to pass over said stop.

6. In a device for inserting separators between successively delivered sheets, a platform to support a stack of separators provided with a retaining stop at the edge thereof and means to secure intermittent pressure of the stack against the stop, in combination with means for elevating a separator to permit its bottom to pass over the stop.

7. In a device for inserting separators between successively delivered sheets, a support for a stack of separators, means for elevating a separator from the stack and resilient means contacting with the top of the separator when elevated to move it out from the stack and force it downward.

8. In a device for inserting separators between successively delivered sheets, means for

releasing a separator from a collection thereof, and a member arranged to contact with the separator and exert force against it in a direction to further its delivery to a delivered sheet.

9. In a device for inserting separators between successively delivered sheets, means for releasing a separator from a collection thereof, and a member arranged to contact with the separator and exert force against it to further its delivery to a delivered sheet, said member being moved by a force independent of the sheet delivering mechanism, the operation of which is timed by connection with said mechanism.

10. In a device for inserting separators between successively delivered sheets, a frame providing support for a collection of separators, two shafts supported by the frame, each connected with the sheet feeding mechanism for intermittent movement timed by its operation, means for detaching a separator from the stack operated by the movement of one shaft, and means for exerting force against the detached separator operated by the movement of the other shaft.

11. In a device for inserting separators between successively delivered sheets, a support for holding a stack of separators in vertical position, and means for moving the external separator relative to the stack comprising a gripping member movable by bell crank mechanism operatively connected with the sheet feeding mechanism.

12. In a device for inserting separators between successively delivered sheets, a support for holding a stack of separators in vertical position, means for moving a separator relative to the stack comprising a contacting device movable by connection with the sheet feeding mechanism, and means for intermittently moving and holding said device away from the stack.

13. The combination with means for delivering printed sheets successively, of a series of separators consisting of material of stiffness and strength suitable to withstand the action of a force exerted against them to assist them into position between the printed sheets, each of said separators being provided with a hole and the separators being arranged in a stack with the holes all in alignment, and a device for inserting the separators successively between the delivered sheets comprising, means for supporting the stack of separators, means for moving a separator to bring its hole out of alignment with the holes in the other separators, and means adapted to act through the aligned holes and exert force against the moved separator to assist in delivering it to a delivered sheet.

14. The combination with means for delivering printed sheets successively, of a series of separators consisting of material of stiffness and strength suitable to withstand

the force of a plunger exerted against a portion thereof and provided with a hole adapted to permit the passage of the plunger therethrough, said separators being arranged in a stack with the holes all in alinement, and a device for inserting the separators successively between the delivered sheets comprising, means for supporting the stack of separators, means for moving a separator so that its hole is out of alinement with the holes in the other separators, a plunger adapted to pass through the alined holes and strike the moved separator to assist in pushing it to a delivered sheet, and means for actuating the plunger.

15. 15. The combination with means for delivering printed sheets successively, of a series of separators consisting of material of stiffness and strength suitable to withstand the force of a plunger exerted against a portion thereof and provided with a hole adapted to permit the passage of the plunger therethrough, said separators being arranged vertically in a stack with the holes all in alinement, and a device for inserting the separators successively between the delivered sheets

comprising, means for supporting the stack of separators, means for separating a separator from the stack and permitting it to fall to a position in which its hole is out of alinement with the holes in the other separators, a plunger adapted to pass through the alined holes and strike the separated separator to assist in pushing it onto a delivered sheet, and means for actuating the plunger.

16. The combination with means for delivering printed sheets successively, of a series of separators, each separator having a hole therein, and the separators being arranged in a stack with the holes all in alinement, and a device for interleaving the printed sheets with the separators comprising, means for holding the stack of separators, means for moving one of the separators to a position in which its hole is out of alinement with the holes in the other separators, and means adapted to act through the alined holes to exert force against the moved separator to further its delivery onto a delivered sheet.

ERNEST JOSEPH BRASSEUR.
